CLAIM

The ornamental design for a spray gun, as shown and described.

DESCRIPTION

1. Spray gun
1.1 : Front
1.2 : Back
1.3 : Top
1.4 : Bottom
1.5 : Left
1.6 : Right
1.7 : Perspective view showing front side
1.8 : Perspective view showing rear side
This article is a spray gun that applies chemicals, parting agents, glue, coating materials or the like; the features shown in dotted lines depict environmental subject matter only and form no part of the claimed design (disclaimer); thin lines drawn on the surfaces of this article is shading lines identifying a shape of a three-dimensional surface.

1 Claim, 8 Drawing Sheets(56)
